APPARATUS FOR MINIMIZING DISTORTION
OF ALUMINUM AND SIMILAR SHEETS

John C. L. Foultz, Tarentum, Pa.

Application May 10, 1940, Serial No. 334,367

5 Claims. (Cl. 266—2)

This invention relates to apparatus for preventing distortion of aluminum sheets during the manufacturing procedure employed in producing them.

In the manufacture of commercial aluminum sheets it is considered necessary, or at least highly desirable, to heat treat them by an immersion in a bath of molten nitrate or similar material. After the sheets have been so immersed and consequently have been heated to substantially the temperature of the heat-treating liquid, they are withdrawn from the bath and quenched, ordinarily by being immersed in water existing at or about atmospheric temperature. It has been found that sheets subjected to this treatment sometimes wrinkle and buckle to such an extent that it is difficult to straighten them by ordinary and usual cold stretching operations.

My invention is two-fold in its character. It contemplates apparatus for subjecting the sheets to tension while they are maintained at the heat-treating temperature; i. e., at about the temperature of the hot tempering liquid. It also contemplates apparatus for so applying the tensional forces that all portions of each sheet are substantially uniformly stressed while the sheet is in a condition to effectively respond to the stresses set up in it.

In the drawings accompanying and forming a part of this application, Figure 1 is a perspective view of sheet-tensioning apparatus which may be employed for the purpose of subjecting a plurality of sheets to tensional forces prior to, during and after they are immersed in the heat-treating liquid; Figure 2 is a fragmental sectional view of apparatus embodying the features disclosed in Figure 1, but including facilities for mounting and supporting more sheets than are capable of being mounted and supported on the apparatus of Figure 1. The section of Figure 2 is taken along a line corresponding to the line II—II of Figure 1. Figure 3 is a fragmental side elevation of a sheet-clamping device which may constitute a detail of the apparatus illustrated in Figures 1 and 2; Figure 4 is a plan view of the device shown in Figure 3; and Figure 5 is a fragmental front elevation of the device shown in Figures 3 and 4.

The apparatus here illustrated includes a beam 11 which is capable of being suspended and which is so associated with auxiliary equipment that it is capable of supporting a number of separate sheets while they are subjected to tensional forces and while they are held in a posi-

tion convenient for immersion in a treating-liquid, such, for example, as molten sodium nitrate. As shown, the beam 11 is in the form of an I-beam, which is provided with crane hooks or similar devices 12 located intermediate its ends and so arranged as to facilitate suspending the beam while it is retained in a horizontal position. The beam 11 is adapted to support two cages 13 which are movable toward and away from each other, lengthwise of the beam, and are adapted to be rigidly secured in adjusted positions at points along the beam.

Each cage may consist of a box-like structure open at its inner and outer sides and adapted to receive a plurality of sheet-clamping and tensioning devices 10. For this purpose, each cage 13 is shown as provided with cleats or guides 14 which extend across the top and bottom of the cage and which cooperate with each other and with the side walls 15 of the cage to provide a separate positioning compartment or way in which each sheet-clamping and tensioning device may be mounted.

In the apparatus illustrated, each cage may be bolted to the supporting beam 11 and in Figure 1, I have illustrated the beam as provided with two longitudinally extending bolt-receiving slots 16 which are adapted to cooperate with supporting straps 17, with which the cages are provided, in supporting and in securing the cages in adjusted positions along the beam. As shown, a pair of straps 17 is secured to the top of each cage with the straps of each pair located in spaced relation and positioned so that the bottom flange and the web of the I-beam 11 are located between them. Bolt holes are formed in these straps so as to cooperate with the slots 16 and bolts 18 extend through the holes and the slots and are employed for the purpose of rigidly securing each cage in position along the beam 11.

It will be understood that each cage is adapted to support one end of each sheet while the same is being subjected to the heat-treating effect of the molten sodium nitrate. It should also be understood that the sheets to be treated are located in parallel relation, both as to the beam 11 and as to each other; that they span the space between the two cages and are so located that their extended surfaces extend vertically. That is to say, the sheets are so carried by the support apparatus as to facilitate their movement into and out of such treating liquids as are employed and so as to insure that each sheet will rapidly respond to the temperature of the treat-

ing liquid without being materially affected by an adjacent sheet.

Each sheet is adapted to be engaged by two sheet-clamping and tensioning devices 10 which are applied to its opposite ends. In Figures 3, 4 and 5 I have illustrated a form of such devices which may be employed with a support apparatus such as illustrated in Figures 1 and 2. As there shown, each sheet-clamping and tensioning device 10 consists of a box-like structure 20, which is open along one side, and a rotatable clamping element 21 which is located within and extends lengthwise of the housing.

Each element 21 is provided with a substantially cylindrical body portion and two cylindrical trunnions 22 which are eccentrically located with relation to the body portion and are journaled in cross supports 23. Each trunnion is shown as provided with apertures 22' for receiving adjusting bars, similar to capstan bars, for the purpose of turning the element 21 so that its cylindrical body portion moves to a sheet-clamping position, with relation to one of the walls of the housing 20. Each clamp and tensioning device 10 is adapted to be located in one of the positioning compartments formed by the transverse cleats 14. A reference to Figures 1 and 2 discloses that each cage 13 is adapted to receive several of the devices 10, and that each such device is located in an upright position so that the clamping surfaces thereof extend vertically.

In order to facilitate positioning the clamping devices 10 in the cages 13, each device is provided with caster rollers 24 located on the top and also the bottom thereof. In addition, each cage is provided with removable bars 25 which, when removed, give free access to the interior of the cage but, when in place on the cage, prevent the devices 10 from moving out of the cage. It should, however, be said that each device 10 is free to move along its positioning compartment or way, i. e., toward and away from its companion device 10 located in the opposed cage 13, and is adapted to cooperate with its companion device in holding a sheet in place in the supporting apparatus.

The operation of loading sheets to the supporting device so that it is properly positioned with relation thereto, involves securing one of the tensioning devices 10 to each end of each sheet. This is accomplished by introducing the end of the sheet into the open side of the housing 20 and between the body portion of the cylindrical member 21 and the adjacent side wall of the box-like structure. The cylindrical element 21 is then turned about its trunnions 22, so as to force it into engagement with the sheet and so as to clamp the sheet between it and the adjacent wall of the housing 20. As shown in Figure 4, the trunnions 22 are so located with relation to the cylindrical body portion of the element 21 that the pull of the sheet clamped into position as above described, tends to increase the clamping action in that it tends to force the cylindrical surface into more intimate engagement with the sheet and also tends to press the sheet more firmly against the cooperating clamping surface of the housing 20.

In the apparatus illustrated, both the cages 13 are adjustable longitudinally of the supporting beam 11 for the purpose of accommodating sheets of different lengths. Each clamping device 10 is movable, with relation to its supporting cage, for the purpose of facilitating the handling of the

sheets but primarily for the purpose of subjecting the sheets to tension after they are mounted on the supporting apparatus. That is to say, each clamping device 10 is movably mounted in one of the cages 13 and is moved to different positions with relation to the cage during the operation of subjecting the sheet associated therewith to tensional strains.

While the clamping devices 10 of one cage 13 may be immovably mounted on that cage, and while the sheet-tensioning operation may be accomplished by the individual application of the active tensional force to but one of the two clamping devices secured to each sheet, I have shown means for simultaneously applying the tensional forces to all of the clamping devices 10 and under such conditions that all those devices are capable of moving, during the application of the tensional forces, in order to transmit tensional stresses to the associated sheets.

In the drawings, the beam 11 is shown equipped with tension-applying means in the form of cables, pulleys and cable drums so arranged as to place each sheet under tension. A shaft 26 is journaled in bearings carried by housings 27 which are secured to a base 28 mounted on and secured to the top flange of the beam 11. These bearing housings carry the crane hooks 12, here-tofore mentioned, and they also provide a support for a shaft 29 which carries a pawl 30 adapted to engage a ratchet wheel 31 rigidly mounted on the shaft 26. The pawl 30 is yieldingly pressed against the ratchet by a flat spring 32. The shaft 26 is provided with two cable drums 33—33', each of which is rigidly secured to it. Each drum is associated with two cables, one extending toward one end of the beam 11 for the purpose of applying tension to the clamping devices 10 in one cage 13, and the other extending toward the other end of the beam for a similar purpose in connection with the tension devices housed within the other cage. As shown, cables 34 and 34' extend from the respective drums 33 and 33' to bars 35, each of which may be compared to a whipple tree in that each transmits the pull of the tensioning mechanism to the sheets acted upon.

Figure 1 discloses three cables 36a, 36b and 36c, secured to each bar 35 and each cable is secured to one of the clamping devices 10. Each such cable (36a, 36b, 36c) is secured to its respective bar 35 by means of a coil spring 37. Each cable is also provided with a length-adjusting device, shown in the form of a turnbuckle 38, for the purpose of independently adjusting the positioning of the associated clamping device 10 or for the purpose of individually controlling the application of the tensional force to that device and to the sheet to which it is clamped.

In Figure 1 of the drawings, I have diagrammatically illustrated the sheet-supporting apparatus as adapted to support but three sheets. This, however, is merely for convenience of illustration, since it is contemplated that each such apparatus will be so constructed that it will support a relatively large number of sheets. Each clamping device illustrated is in some way rigidly, and preferably permanently, secured to one of the cables 36a, 36b and 36c. As illustrated, this is accomplished by spreading the strands of the cable at the end thereof and welding the separate strands to the housing 20, of the particular clamping device 10 involved, so that the connection between the housing and cable is

located at a point substantially midway between the ends of the housing.

In order that the turning of the drums 33 may be employed for the purpose of imposing tension on the sheets supported by, and bridging the space between the cages 13, I have provided idler pulleys 41 and 42 for guiding the cables 36a, 36b and 36c. The pulleys 41 are mounted on an idler shaft 43 and the pulleys 42 are shown mounted on an idler shaft 44. Both the shafts 43 and 44 are journaled on a housing 45 which is secured to the top flange of the beam 11 and, in effect, straddles the adjacent cage 13. With such an arrangement, the turning of the cable-drum shaft 26 tensions the cables 34, 34' and in this way moves or tends to move the clamping devices 10, of the opposed cages 13, away from each other and thus imposes tensional stresses of the desired magnitude upon each of the sheets carried by the supporting apparatus.

In Figure 2, I have indicated that the supporting apparatus may be so constructed as to carry at least six pairs of clamping devices 10 and consequently at least six sheets to be heat treated. This view also discloses that each sheet will be associated with two tension-imposing cables so arranged as to impart the desired tension to it while it is secured in place in the supporting apparatus.

While there is a permissible variation in the way the illustrated apparatus may be employed, it will be understood that the apparatus is primarily designed to not only support the sheets while they are submerged in the hot heat-treating liquid, but also to so support them that each sheet is capable of being maintained under tension with the tensional stresses substantially uniformly distributed throughout the sheet, during the period it is subjected to the heat treatment. A convenient procedure for accomplishing this is to mount the sheets in place on the supporting apparatus and then manipulate the shaft 26 to impose the desired tensional strains on each sheet as a preliminary to introducing the sheets into the heat-treating liquid. In this way, the individual cables 36 can be adjusted as to length by means of the turnbuckles 38, and observation of the coil springs 37 will give some indication as to the distribution of the tensional forces as among the various sheets, it being understood that it is desirable to so distribute the tensional stresses that all the sheets are strained substantially the same amount.

After tension is thus imposed on all of the sheets secured to the supporting apparatus, the apparatus is manipulated in such a way as to lower the sheets into a tank of the heat-treating liquid, i. e., into a tank of molten sodium nitrate or similar material. The proportions of the tank will be such as to completely submerge each sheet in the molten material and under conditions such as to insure a uniform distribution of heat throughout each sheet.

It will be apparent that the apparatus illustrated accommodates this procedure without causing the tension-imposing mechanism to contact the heat-treating liquid. That is to say, the shaft 26, the cable drums 33, the coil springs 37 and the turnbuckles 38 are all above the heat-treating liquid and are accessible throughout the entire heat-treating operation. With this arrangement, the springs 37 can effectively function to maintain a tensional strain on each sheet and independently of the yield of the sheet to

the force and independently of the expansion of the sheet in response to the heat-treating temperature. With this in mind, it will be apparent that the initial adjustment of the mechanism, in applying the desired tensional force to each of the various sheets, will involve an appreciable extension of each spring 37 so that it will be capable of maintaining a substantially constant tensional stress in the associated sheet throughout the entire heat-treating operation.

For this reason, I prefer to employ apparatus such as illustrated in Figure 1, i. e., apparatus wherein all clamping devices 10 are movably mounted in their respective supporting cages 13 and are movable in response to the operation of applying tension to the sheets. I also prefer the arrangement of apparatus illustrated wherein each cable (36a, 36b, 36c) is provided with a length-adjusting device 38 and a coil spring 37 since this arrangement divides the tensional stresses between two springs and thus makes it possible to more nearly maintain a substantially equal stress on each sheet and independently of the degree of yield and the amount of expansion encountered in each sheet while it is being raised to the temperature of the heat-treating liquid.

The apparatus illustrated also makes it possible to maintain each sheet under substantially the same tensional stress throughout the quenching operation. It will be understood that the sheets will preferably be retained in place on the supporting apparatus and under tension while being removed from the heat-treating liquid and while being immersed in and removed from the quenching liquid. It will, therefore, be apparent that the apparatus accommodates both the heating and the cooling of the sheets and under conditions such that each sheet is subjected to substantially the same tensional strain throughout both operations.

I have not attempted to do more than define the characterizing features of my invention, insofar as it involves the apparatus here illustrated. For this reason, I desire to have it understood that I have not attempted to design specific structural details such, for example, as the clamping devices and the mechanism in such a way as to most effectively conserve space.

I, however, do wish it to be understood that in the preferred embodiment of my invention, all parts of the apparatus are to be fabricated from material which will effectively withstand the variations in temperature to which the apparatus is necessarily subjected and that the tensioning mechanism must be such that the tensional stresses in each sheet can be separately controlled and can be so applied as to impose a substantially uniform strain throughout all portions of the sheet. In addition, the tension should preferably be applied under conditions such as to maintain the sheet under tensional stress throughout the entire heat-treating and quenching operation.

It will also be apparent that various changes may be made in the structural details of the apparatus herein described and illustrated without departing from the spirit and scope of my invention as defined by the appended claims.

Having thus described my invention, what I claim is:

1. A sheet-supporting apparatus for use in sheet-tensioning operations, comprising a support member, two cages mounted in spaced relation on said member, means for adjusting the position of one such cage along said member, a

plurality of sheet-clamping devices supported by each such cage with the devices of one cage movably supported thereby and tension-imparting means carried by said support member for simultaneously moving all said movable devices to impart tension to the sheets engaged thereby.

2. Sheet-tensioning and supporting apparatus for use in sheet-tempering operations, comprising a support member, cages mounted thereon in spaced relationship, means for supporting a plurality of sheets between said cages comprising a plurality of sheet-clamping devices carried by said cages with some of said devices movable with relation to the carrying cage, means carried by said support member for simultaneously imparting movement to such movable devices to tension the sheets engaged thereby, and separate means for independently positioning each such movable device.

3. A sheet-tensioning and supporting apparatus for use in sheet-tempering operations, comprising a substantially horizontally extending support member, cages depending from said member in spaced relationship, means comprising a plurality of separate sheet-clamping devices carried by each of said cages for engaging sheets to be tempered and for supporting a plurality of such sheets in parallel, spaced relation between said cages, adjustable means carried by said support member for simultaneously actuating at least some such clamping devices to impart tension to the sheets engaged thereby and separate mechanisms forming a part of said tension imparting means for substantially maintaining the tension-imparting forces exerted by such clamping devices independently of the expansion of the sheets engaged thereby.

4. In a sheet-supporting apparatus for use in sheet-tempering operations, a substantially hori-

zontally extending support member, means for supporting a plurality of sheets in parallel spaced relation below said member and in substantially parallel relationship to said member, comprising two cages depending from said member and located in spaced relationship thereon, a plurality of vertically extending sheet-clamping devices carried by each such cage and located in parallel relationship thereon, means carried by said support member for simultaneously moving at least some of said clamping devices to impart tension to the sheets engaged thereby, separate means for independently positioning at least some of said clamping devices and separate means for substantially maintaining the tension-imparting force exerted by at least some of said clamping devices independently of the expansion of sheets engaged thereby.

5. In a sheet-supporting apparatus for use in sheet-tempering operations, a support member, means for supporting a plurality of sheets in parallel spaced relationship below said member and with the faces of said sheets extending substantially vertically, comprising two cages depending from said support member and located in spaced relationship therealong, a plurality of sheet-clamping devices carried by each such cage with some such devices movable with relation to the carrying edge, adjustable tension-imparting means carried by said support member above said cages for simultaneously moving said movable clamping devices to impart tension to sheets engaged thereby, and separate means for substantially maintaining the tension-imparting force exerted by at least some of said clamping devices independently of the expansion of the sheets engaged thereby.

JOHN C. L. FOULTZ.
